UNITED STATES PATENT OFFICE.

AARON S. NICHOLS, OF NEW YORK, N. Y.

VENEER-DRIER.

No. 918,581.

Specification of Letters Patent.

Patented April 20, 1909.

Application filed February 1, 1908. Serial No. 413,827.

To all whom it may concern:

Be it known that I, AARON S. NICHOLS, a citizen of the United States, residing in New York, in the county of New York and State of New York, have invented a new and useful Improvement in Veneer-Driers, of which the following is a specification.

In Patent No. 674,342, issued to me May 14, 1901, I show a series of steam heated platens arranged horizontally one above another, and opened and closed by mechanism including a steam or other fluid actuated piston located below the series, the topmost platen being held stationary by suitable means so that it can resist the upward thrust of the power mechanism.

My present invention is intended to be used with driers in which the platens are arranged vertically, and are so connected together that the entire series may be opened and closed by applying power to the outermost platens of the series, the object of the invention being to adapt the fluid power mechanism to the vertical platen driers so that the efficiency of such driers may be greatly increased, and their operation rendered easy and noiseless. In the invention also, I have endeavored to avoid the heavy shocks and jars and consequent injury to the driers occasioned when the plates close by the style of operating devices heretofore used with the vertical platen driers, a type of which devices is shown in my Patent No. 515,357, of February 27th, 1894.

The nature of my present improvement is fully disclosed below, and is also illustrated in the accompanying drawing in which—

Figure 1 is a front elevation of my improved drier. Fig. 2 is a partial side elevation. Fig. 3 is a section of one of the platen operating fluid power cylinders. Fig. 4 is a section of the valve controlling the fluid cylinders. Fig. 5 is a section on the line 5—5 of Fig. 4 and Fig. 6 is a partial plan of the platens. Fig. 7 is an elevation of the cam wheel.

In said drawing, 6—6 represent the vertical platens, each hung upon straps 7 at its ends, the straps being pivoted at 8 to overhead supports so as to permit free swinging by the platens in lateral directions. Vertical corner columns 9 and horizontal beam 10 form a part of the frame of the drier, and

11 are braces for stiffening the structure. Between each pair of columns 9 and opposite the platens are I beams 12, and each of such beams supports a hydraulic cylinder 13 by a pivot joint 14 adapted to permit the body of the cylinder to swing vertically and accommodate itself to the changes in position of the platens. The pistons 15 of the cylinders are pivotally united to heads 16 secured to the outer faces of the outermost platens as plainly shown. It will be noted in this construction, that any movement imparted to the pistons in directions toward the platens will tend to close the latter upon the veneers, while any movement in the opposite directions, *i. e.* away from the platens, will tend to open or separate them. In order that the opening movements of the outer platens may with certainty cause a spreading or opening of the intermediate platens, I connect the latter to the outer platens by lazytongs, consisting of a series of links 17 pivoted at their ends to each other and at their centers to the platens as explained in said Patent 515,357. It will also be noted from the description of the water connections given below that they possess sufficient flexibility to permit the rising and falling movements of the cylinders.

The cylinders receive their water supply from a common source, are controlled by a single valve and act always in opposite directions. The water supply pipe is shown at 20 and 21 and 22 are connections leading directly from it to the cylinders. The pistons 15 of the latter have unequal areas exposed to the water at their opposite sides, and said connections 21 and 22 enter the cylinders upon the sides of the pistons having the lesser areas. No valves need be used in these connections, so that the pressure therefrom is constant. The water supply to the greater area side of the pistons passes through the controlling valve 23. The casting 24 of this valve has a port 25 connecting with the supply pipe, a port 26 connected by pipes 27 and its branches 28 and 29 to the cylinders at the greater area side of the pistons, and a discharge port 48. The valve is shown as connecting the feed port with port 26, and is capable of being shifted by the lever 49 so as to cut off the feed and connect the port 26 with the discharge. Whenever

the feed is connected to the port 26, the water enters the cylinders upon the large area side of the pistons and sufficient power is thereby imparted to them to overcome the 5 constant pressure on the other side thereof and force the water upon that side back into the feed pipe, and to close the platens upon the veneers being dried. And this closing movement is so gradual as to be noiseless and 10 occasion no shock or jar to the apparatus, the resistance upon the lesser area side of the pistons tending to cushion the close of the platens and to prevent the shocks and jarring which would otherwise occur. In 15 like manner when the valve is shifted to cut off the feed water and open the discharge, the outgoing water on the power side of the pistons cushions the opening movement of the platens which then takes place and renders that movement also noiseless and free from shock.

The valve operating lever 49 is connected to proper periodically acting actuating mechanism by the rod 30. This mechanism is 25 preferably constructed as follows: An elbow lever 31 pivoted at 32 has one arm joined to said rod 30 as shown, and its other arm carries an anti friction roller 33, at its upper end. This roller is so located as to insure its contact with a plurality of oppositely acting cams 34 and 35 mounted upon a cam wheel 36 carried by shaft 37 operated by the pinion 38 meshing with gear 39 on a second shaft 40 which is suitably connected to a 35 source of power. The cam 34 is adapted to shift the valve from the open position, *i. e.*, the position in which the water is discharged from the larger area side of the pistons and in which the platens are opened, to the closed 40 position in which the water is admitted to said larger area side, thus closing the platens while the cam 35 acts to shift the valve back to the first mentioned or open position, thus causing the opening of the platens. As 45 the platens should remain open for only an instant of time, except at the finish of the drying, the cam 35 is immediately followed by a cam 34 so that the platens will be closed almost immediately and before the veneers 50 become chilled. The cam wheel may carry such number of these cams as may be necessary to give the required number of opening operations which may differ with different woods and different thicknesses of veneers, 55 and they should be arranged on the wheel so as to produce short open periods and comparatively long closed periods.

I claim:—

1. The combination with the series of vertical, movable platens of oppositely acting hydraulic cylinders attached to the outer platens, and adapted both to close and open the platens.
2. The combination with a series of ver-

tical platens suspended by supports which 65 permit them to swing, of oppositely acting fluid cylinders attached to the outer platens and pivotally supported.

3. The combination with a series of vertical platens suspended by supports which 70 permit them to swing, of oppositely acting fluid cylinders attached to the outer platens, said cylinders having pistons whose opposite faces are of unequal area.

4. The combination with a series of vertical platens suspended by supports which 75 permit them to swing, of oppositely acting fluid cylinders attached to the outer platens, said cylinders having pistons whose opposite faces are of unequal area, means for admitting to the cylinders at one side of the pistons a constant supply of water under pressure, and means for admitting to the other side of the pistons a regulated supply 80 of water under pressure.

5. The combination with the series of vertical, movable platens of oppositely acting hydraulic cylinders attached to the outer platens, and adapted both to close and open 90 the platens and a single valve controlling both cylinders.

6. The combination with a series of vertical, movable platens of oppositely acting hydraulic cylinders attached to the outer 95 platens, and adapted both to close and open the platens, said cylinders having pistons whose opposite faces are of unequal area, and a valve regulating the supply of the water to one side of the pistons.

7. The combination with the series of vertical, movable platens of oppositely acting hydraulic cylinders attached to the outer 100 platens, and adapted both to close and open the platens, said cylinders having pistons which are of unequal area upon their opposite faces, a valve controlling the admission 105 of water to the larger faces of the pistons, and periodically acting mechanism for operating said valve.

8. The combination with the series of vertical, movable platens, of oppositely acting hydraulic cylinders attached to the outer 110 platens, and adapted both to open and close the platens, and periodically acting mechanism controlling both the opening and closing 115 of the platens.

9. The combination with the series of vertical, movable platens, of oppositely acting hydraulic cylinders attached to the outer 120 platens, and adapted both to open and close the platens, said cylinders having pistons which are of unequal area upon their opposite faces, a valve controlling the admission 125 of water to the larger faces of the pistons, and periodically acting mechanism for operating said valve in both directions.

10. The combination with a series of vertical platens adapted to swing laterally, and

provided with means whereby they may be spread apart by the swinging of the outer one of the series, of a hydraulic cylinder attached to and operating said outer platen positively in both directions, and controlling devices causing periodical operations by said cylinder.

11. The combination with a series of vertical platens adapted to swing laterally, and

provided with means whereby they may be ¹⁰ spread apart by the swinging of the outer one of the series, of a hydraulic cylinder attached to and operating said outer platen positively in both directions.
